(57) **CLAIM**

The ornamental design for a chair base, as shown and described.

DESCRIPTION

FIG. 1 is a perspective view of a chair base in accordance with a first embodiment of the present invention;
FIG. 2 is a front view of the chair base of FIG. 1;
FIG. 3 is a rear view of the chair base of FIGS. 1 and 2;
FIG. 4 is a top view of the chair base of FIGS. 1-3;
FIG. 5 is a bottom view of the chair base of FIGS. 1-4;
FIG. 6 is a side view of the chair base of FIGS. 1-5, the opposite side being a mirror image thereof;
FIG. 7 is a perspective view of a chair base in accordance with a second embodiment of the present invention;
FIG. 8 is a front view of the chair base of FIG. 7;
FIG. 9 is a rear view of the chair base of FIGS. 7 and 8;
FIG. 10 is a top view of the chair base of FIGS. 7-9;
FIG. 11 is a bottom view of the chair base of FIGS. 7-10; and,
FIG. 12 is a side view of the chair base of FIGS. 7-11.
The broken lines shown in the Figures are for environmental purposes only and form no part of the claimed design.

1 Claim, 8 Drawing Sheets
